STEPHEN P. SANDERS, OF CUPERTINO, CALIFORNIA.

CARBURETER.

1,105,160.

Specification of Letters Patent. Patented July 28, 1914.

Application filed August 12, 1913. Serial No. 784,348.

To all whom it may concern:

Be it known that I, STEPHEN P. SANDERS, a citizen of the United States, residing at Cupertino, in the county of Santa Clara and State of California, have invented new and useful Improvements in Carbureters, of which the following is a specification.

This invention relates to a carbureter especially constructed for vaporizing volatile liquids for heating, lighting and cooking purposes.

The purpose of the present invention is to provide a simple, cheaply-manufactured, easily-adjusted carbureter which is compact in construction and automatic in operation.

The main object of the invention is to provide means for making a vaporizing of absolute uniformity, and to provide means which will prevent any unvaporized fuel from escaping through the service pipe of the apparatus.

Further objects will appear hereinafter.

The invention consists of the parts and the construction and combination of parts as hereinafter more fully described and claimed, having reference to the accompanying drawings, in which—

Figure 1 is a central vertical section of the apparatus. Fig. 2 is a section of one of the secondary carbureting chambers. Fig. 3 is an enlarged view of the fuel feeding mechanism. Fig. 4 is an enlarged section of the carbureter tube. Fig. 5 is a side elevation of the apparatus. Fig. 6 is an enlarged detail view of the water valve operating mechanism.

Referring to the drawings: A indicates a tank adapted to contain water. Slidably mounted within the tank is a bell 2 of the usual construction, and suitably secured in the top portion of same and extending downwardly is a plunger shaft 3 having a snug sliding fit in a ram cylinder 4, which cylinder projects up from the bottom of the tank A, and is open below to a suitable source of fluid pressure supply. The fluid is admitted and discharged to and from the ram cylinder 4 beneath the plunger 3 so as to reciprocate the bell 2. The means for admitting and discharging water from the ram cylinder 4 will hereinafter be described.

Suitably arranged within the tank A is a carbureting cylinder 5 and an oil well 6, both of which are secured to the bottom of the tank and open at their upper ends which project up into the bell 2 above the

water level. The carbureting cylinder 5 is filled with a plurality of cup-shaped perforated disks 7, which are covered with a suitable form of thin cloth, as indicated at 60 7'. The well 6 is so connected with a source of hydrocarbon supply that a quantity of same is always maintained within the well. A predetermined quantity of liquid is dipped up from the well 6 at convenient intervals 65 by means of a bucket 8 and disposed into the carbureting cylinder 5 above the disks 7, to become absorbed and thoroughly distributed by the fabric covering of same. Air is drawn into the bell 2 through an inlet 70 valve 9 which opens to admit air as the bell is raised. The exhaust from the bell, as it falls, occurs through the carbureting cylinder 5 so that the air becomes thoroughly saturated to form a rich illuminating or fuel 75 mixture as it passes through the fabric-covered disks within the cylinder. The periodical delivery of liquid into the carbureting cylinder 5 is accomplished by the following mechanism: 8 indicates a bucket carried by 80 a rod or wire 10 which depends from a radially extending arm 11, suitably attached to the plunger 3. The bucket is pivoted off center with relation to the suspending rod 10 so as to normally assume a tilted position 85 with relation to the rod. The tilting movement of the bucket is however limited by a set screw 8' secured upon a bracket extending from the rod. The bucket, when filled with liquid, will thus normally assume the 90 inclined position shown in Fig. 3; and will, when elevated to a certain point engage with a projection 12 which is positioned with relation to a duct 13 connecting the well with the carbureting cylinder 5, and become tilted 95 into the opposite direction where it automatically discharges its contents into the duct 13; here it is immediately conveyed to the carbureting cylinder and distributed over the several disks within same. The amount of 100 fuel elevated by the bucket 8 can thus be varied by adjusting the bucket to assume a more or less inclined position. The vapor produced by forcing air through the saturated fabric covering the perforated disks 7 105 is conveyed through a pipe 14 to a receiver of suitable construction. The distillate or other hydrocarbon liquid from which the vapor is made may be stored in any desired or convenient manner or place so long as a 110 constant supply is maintained in the well 6. In this case I have shown the receiver and

distillate supply tank as combined in a single structure.

B represents a tank adapted to contain water, and slidably mounted in same is a bell 15 of suitable construction. Supported within the tank on a standard 16 is a submerged oil tank 17, from the bottom of which extends a pipe 18 connected with a well 6 in the bottom of the tank A. The tank 17 is designed to be filled through a pipe 19, which connects with the pipe 18 between the tanks A and B, having its filling end about on a level with the top of the oil tank 17. A removable cap 20 is provided on the end of the pipe 19 to prevent evaporation. An air vent pipe 21 extends up through the tanks B and 17 and terminates in a dome 22 in the top of the tank 17. The lower end of the pipe 21 is open to the atmosphere to permit egress and ingress of air to and from the oil tank during the filling or discharging of the latter.

A suitable form of check valve 23 is mounted on the pipe 18 to prevent the liquid from being forced back out of the well 6 on the descent of the bell 2. The pipe 14, through which exhaust from the carbureting tube takes place, passes up through the bottom of the tank B and terminates above the water level in the dome of the bell 15. A check valve 24 is provided on the pipe 14 to prevent the product from the reservoir from passing back into the generating tube 5.

Interposed between the pipe 14 and the service pipe 25, at any convenient point between the tanks A and B, is a series of secondary carbureting chambers generally indicated at C. These secondary carbureting chambers are here shown as consisting of T-shaped members 26 which are closed at their lower ends by hollow caps 27. The several members C are connected by suitable elbows 28 and projecting down into the bottom of the caps 27, on the elbow connections 28, are tubes 29 provided with screen caps 30 on their lower ends. Any unvaporized fuel escaping from the carbureting tube 5 will naturally drain down through the pipe 14 and connections 14' into the several caps 27. For the purpose of equally distributing such trapped unvaporized fuel throughout the several chambers a series of connecting pipes 29' and 30' have been provided, through which the trapped liquid may be conveyed from one chamber to another. The unvaporized fuel is thus prevented from escaping through the service pipe 25 and is furthermore given an opportunity to again vaporize, for the simple reason that the vapor passing through the several chambers C must necessarily pass through the trapped liquid as the pipe 29 extends sufficiently far down into the hollow caps 27 to insure the passage of vapor through the trapped liquid. The vapor in passing through the trapped liquid will thus be further enriched and any

accumulation of trapped liquid will be removed. Any suitable number of secondary chambers C may be provided, said number depending on the size and capacity of the pipe. By adjusting the inclined position of the bucket 8 to increase or decrease the amount of liquid elevated to the carbureting tube 5 it will also be possible to reduce the amount of unvaporized liquid trapped in the hollow caps 27. The capacities of the bell 2 and the bucket 8 are furthermore so proportioned that each rise of the bell 2 draws in a suitable supply of air, which on becoming properly saturated with the volatile hydrocarbon produces a perfect mixture. The lifting or raising of the bell 2 is accomplished by the liquid admitted through the bottom of the ram cylinder, but the weight of the bell with connected plunger is sufficient to fall back by gravity. The air is thus completely exhausted through the carbureting tube 5 and finally admitted to the container 15 where it is stored for use.

Various mechanisms may be employed to regulate the inlet and discharge of water to the ram 4. In the present instance I have shown a three-way valve 31 which is adapted to turn the water from a supply pipe 32 into the ram, or to lead the water from the ram into a discharge pipe 33 and shut off the supply from the pipe 32 accordingly as the bell is lifted or lowered. The operation of the valve is preferably controlled by the rise and fall of the bell. The stem of the valve 31 is secured to a rocking member 34, provided with two stops 35 and 36. The rocking member is so positioned as to have a limited oscillating movement which is only sufficient to open and close the valve. Loosely mounted upon the valve stem is a secondary rocking member 37, upon the upper end of which is fixed a horizontal hollow arm 38, adapted to contain a quantity of mercury or any other shiftable weight for the purpose of causing the arm to rock quickly to turn the valve and immediately cut off or turn on the water from the supply pipe 32. The position of the secondary rocking arm 37 is controlled by a loosely mounted crank arm 39, provided on one end with a weight 40 and on the opposite end with a pair of stops 41 and 42. Normally the rocking arm 37 will stand at an incline to one side or the other of a vertical line, and is supported in this position by either one or another of the stops 41-42 on the crank arm 39. The crank arm 39 is connected by a chain or cord 43 with the bell 2. The function of the crank arm 39 is to lift the arm 37 until the latter approaches or slightly passes the vertical position. As soon as this occurs, however, the mercury or other shiftable weight within the cross-arm 38 causes the arm to instantly descend on the opposite side until it is

stopped by the opposite stop 41. In falling from the position slightly over the vertical into engagement with the stop 41, it will be seen that the arm 37 will strike the stop 35 5 which is secured upon the stem of the valve. The valve stem will thus be rocked sufficiently to cause the valve to assume the desired position with relation to the upward or downward movement of the plunger 10 within the ram cylinder.

The operation of the apparatus is as follows: The tank 17 being filled with a suitable form of hydrocarbon liquid, the latter will flow therefrom into the well 6, through 15 the pipe 18. Assuming the valve 31 to be turned to let in water to the ram cylinder 4, the bell 2 is lifted causing the bucket 8 to dip up a predetermined quantity of fuel which will be discharged into the carbureting 20 tube 5 the moment the bell 2 has drawn in a full charge of air. At that moment the valve 31 is reversed by the falling of the arm 37, and if the receiver 15 is not already filled the bell 2 will begin to descend. This 25 causes the air within the bell 2 to pass through the carbureting tube 5 where it becomes saturated with the volatile liquid disposed over the several disks within the tube. The air then passes through the pipe 14 30 into the receiver, and also through the secondary carbureting chambers C, into the service pipe 25, when the latter is opened to permit of an outward flow.

The secondary carbureting chambers positioned as here shown not only act to enrich the mixture already generated but also prevent any escape of unvaporized liquid through the service pipe, as all fuel escaping from the carbureting tube 5 is collected 40 in the lower portions of the secondary chambers C.

By adjusting the tilted position of the bucket 8 an unnecessary amount of liquid dipped up by same can be entirely obviated. 45 The proportion of oil and air may thus be changed at any time by varying the capacity of the bucket.

The apparatus here shown is simple in construction and reliable in action. The 50 construction of the carbureting means within the tube 5, together with the provision of the secondary carbureting chambers 5, produces a highly volatile mixture of uniform quality, and the provision of the trap 55 chambers in the lower portion of the secondary carbureting chambers provide a

positive means to prevent the escape of the unvaporized fuel.

The materials and finish of the several parts of the apparatus are such as experience and judgment of the manufacturer may dictate.

Having thus described my invention, what I claim and desire to secure by Letters Patent, is:

1. A secondary carbureter including in combination with a main carbureter and the discharge pipe thereof, a series of spaced vertical hollow members below said pipe, hollow caps closing the lower ends of said members, a pipe connected to the discharge pipe and extending through one of the endmost of said members and into the hollow cap thereof, connecting pipes between the several hollow caps, elbows leading from the side of one member to the upper end of the next adjacent member, and a service pipe connected to the other endmost of said members.

2. A secondary carbureter including in combination with a main carbureter and the discharge pipe thereof, a series of spaced vertical hollow members below said pipe, closures for the lower ends of said hollow members, connecting pipes between said hollow members at the lower ends thereof, a pipe connected to the discharge pipe and extending into one of the endmost of said members, connections between the sides of the hollow members and the tops of the next adjacent members, and a service pipe leading from the other endmost member.

3. A secondary carbureter including in combination with a main carbureter and the discharge pipe thereof, a series of spaced vertical hollow members, below said pipe, a connection between the discharge pipe and an endmost of said members to trap any of the hydrocarbon which may enter said discharge pipe, connections between the lower ends of all of said members, other connections between all of said members above the first named connections, and a service pipe connected to the other of the endmost of said members.

In testimony whereof I have hereunto set my hand in the presence of two subscribing witnesses.

STEPHEN P. SANDERS.
